SPOON OR SIMILAR ARTICLE

Arnold Thaler, Highland Park, Ill., assignor to American Home Products Corporation, New York, N.Y., a corporation of Delaware

Filed Sept. 11, 1968, Ser. No. 13,488

Term of patent 14 years

Int. Cl. D7—03

U.S. Cl. D54—12

FIG. 1

FIG. 2

FIG. 3

FIG. 4

FIG. 1 is a front elevational view of a spoon or similar article showing my new design.

FIG. 2 is a side elevational view thereof.

FIG. 3 is a back elevational view thereof.

FIG. 4 is an enlarged section on line 4—4 of FIG. 1.

The essential features of my design for a spoon or similar article reside in the configuration of the handle in combination with the particular type of ornamentation as applied thereto.

I claim:

The ornamental design for a spoon or similar article, substantially as shown and described.
